UNITED STATES PATENT OFFICE.

CASPAR REISCH, OF PÉCS, AUSTRIA-HUNGARY, ASSIGNOR OF ONE-HALF
TO JOHANN BÄCKER, OF PÉCS, AUSTRIA-HUNGARY.

COMBINATION TABLE, BED, WASHSTAND, &c.

SPECIFICATION forming part of Letters Patent No. 762,600, dated June 14, 1904.

Application filed August 16, 1902. Serial No. 119,977. (No model.)

To all whom it may concern:

Be it known that I, CASPAR REISCH, a subject of the Emperor of Austria-Hungary, residing at Pécs, in the Empire of Austria-Hungary, have invented a new and useful Combination Table, Bed, Washstand, &c., of which the following is a specification.

The subject of my invention is a piece of furniture which when in closed condition presents the appearance of an ordinary writing-table, but which can be opened up for use as bed, washstand, dining-table, and copying-press. The construction is such that writing-table, bed, washstand, and copying-press can be employed simultaneously.

My invention is illustrated by the annexed drawings, in which some of the methods of employing the piece of furniture are shown.

Figure 1 is a perspective view of the piece of furniture employed as writing-table. Fig. 2 is a vertical section of the piece of furniture, the top being drawn out, admitting of the apparatus being employed as writing-table and bed. Fig. 3 is a side elevation of the piece of furniture adapted for use as washstand, the top being, moreover, so disposed that the apparatus can also be employed as dining-table. Fig. 4 is a longitudinal section corresponding to Fig. 2, showing the wire mattress in extended condition. Fig. 5 is a detail view, being a section of the front portion of the press-drawer on the line 4-4 of Fig. 1.

d is a supplementary top for writing purposes, hinged at *b b* to the top *a* of the table, so that it can be turned over.

c c are eccentrics working on pins *c'*. They can be turned by hand into the highest or lowest position, as desired, so as to support the supplementary top *d* at a suitable angle.

When not required, the eccentrics, with their pins, can be simply drawn out. The supplementary top *d* can, on removal of the eccentrics *c*, be laid upon the top *a*, or it can, on the pintles of the hinges *b b* being drawn out, be wholly removed.

When the piece of furniture is to be used as dining-table, the top *d* must be turned on its hinges *b b* through about one hundred and eighty degrees, so that it makes a level sur-

face with the top *a* and the two lateral bars *f f*, 50 which are pivoted at *f'* to the top *d*, then used as legs or supports, Fig. 3.

For the purpose of increasing the area of the surface of the table the top *d* is drawn out off the wings or straps *g* of the hinges *b b*, 55 these straps being prolonged, so as to form bars passing through the top *d*. The intermediate space which is thus caused is filled up by a suitable board, or instead of the latter a stool *h* (likewise provided with a place in 60 the piece of furniture) may be suspended in the space to serve as seat for a child.

In Fig. 2 the top *a* is drawn out in front and supported on the legs *c*, so that the bedstead *i* is exposed. In this figure the arrangement of the washbasin *r* can also be seen in retired position. The top *d*, if set in the dotted-line position, may be employed as drawing-board. The stool *h* is employed for adjusting and supporting it, as shown, or 65 instead of the stool *h* any other suitable object may be employed as support, or the top *d* may be drawn wholly from off the straps *g*, turned through an angle of one hundred and eighty degrees, and then pushed onto 70 the straps again, so that the bars *f f* when turned on their pivots *f'* rest on the top *a* and support the top *d*. The stool may also be used for adjusting the height of the washbasin *r*, being so set as to carry the basin on 75 its side or its end, as desired.

If the washstand is to be used, the door *k* at the back of the apparatus must be opened, the boards or extensions *m n* connected by the hinges *l* and in closed condition lying one 85 upon the other, drawn out, and the slab *n* raised into a vertical position, Fig. 3, and the water-reservoir *p* raised, if required, by drawing out the bar *o* from the board *n*. In this manner the washstand can be adjusted in 90 height as required. The reservoir *p* exactly fits the basin *r* when the apparatus is closed. *v* represents brackets for carrying the slop-pail *w*.

Fig. 4 shows how the bed is used. The end 95 *s* of the space *i* is removable, its extremities fitting into grooves *s'* in the sides *s'* of the table. This end *s* must first be removed and

the levers *t* turned over on their pins *x* from the dotted-line into the full-line position, whereby the wire mattress *u* is stretched and the length of the bed considerably increased.

5 It is obvious that the usual bedding can be laid upon the mattress *u*. The bedding may ordinarily be kept in the space *i*.

A drawer in front of the writing-table serves for the copying-press. The copying-book is 10 placed between the rigid partition or wall *z* and the parallel wall *y*, which can be advanced toward the former by the screw *q* for the purpose of pressing the book lying between the two. The screw *q*, as Fig. 5 shows, is an ordinary copying-press screw secured to the wall *y* in well-known manner and working 15 in the front of the drawer. Its head is shown as square, so that it may be turned by a key.

Having thus described my invention, what 20 I claim as new, and desire to secure by Letters Patent, is—

1. A piece of furniture having the external form of a writing-table with a sliding top *a*, hinges *b* having straps *g*, secured to the said 25 top, a supplementary top *d* through which the said straps pass, so that it can be turned over to form a plane extension of said top *a*, a bed exposed on drawing forward said top *a*, and a draw-out washstand located below said 30 bed, substantially as described.

2. A piece of furniture having the external form of a writing-table with a sliding top *a*, hinges *b* having straps *g*, secured to the said top, a supplementary top *d* through which 35 the said straps pass, so that it can be turned over to form a plane extension of said top *a*, a chamber *i* exposed on drawing forward said top *a*, hinged lever mechanism *t* located within said chamber and capable of being opened 40 out, and a wire mattress secured to said mechanism *t* and to the opposite end of the chamber, and a draw-out washstand located below said bed, substantially as described.

3. A piece of furniture having the external

form of a writing-table with a sliding top *a* 45 hinges *b* having straps *g*, secured to the said top, a supplementary top *d* through which the said straps pass, so that it can be turned over to form a plane extension of said top *a*, a chamber *i* exposed on drawing forward said 50 top *a*, hinged lever mechanism *t* located within said chamber and capable of being opened out, and a wire mattress secured to said mechanism *t* and to the opposite end of the chamber, and two draw-out extensions 55 *m n* hinged together, located below said bed, a washbasin supported by the lower extension *m*, and a water-reservoir carried by the upper extension *n*, all substantially as described. 60

4. A piece of furniture having the external form of a writing-table with a sliding top *a* hinges *b* having straps *g*, secured to the said top, a supplementary top *d* through which 65 the said straps pass, so that it can be turned over to form a plane extension of said top *a*, a chamber *i* exposed on drawing forward said top *a*, hinged lever mechanism *t* located within 70 said chamber and capable of being opened out, and a wire mattress secured to said mechanism *t* and to the opposite end of the chamber, and two draw-out extensions *m n* hinged together, located below said bed, a washbasin supported by the lower extension *m*, and a water-reservoir carried by the upper extension *n*, and a drawer in the writing-table, two plates located within said drawer 75 adapted to receive a copying-book between them, and a screw for actuating the movable plate from the outside of the drawer, all substantially as described. 80

In testimony whereof I have signed this specification in the presence of two subscribing witnesses.

CASPAR REISCH.
